UNITED STATES PATENT OFFICE

CHARLES W. LOGAN, OF KENMORE, NEW YORK

DESIGN FOR AN ELECTRIC LAMP

Application filed July 15, 1939. Serial No. 32,053. Term of patent $3\frac{1}{2}$ years.

To all whom it may concern:

Be it known that I, CHARLES W. LOGAN, a citizen of the United States, residing at Kenmore, in the county of Erie and State of New York, have invented a new, original, and ornamental Design for Electric Lamp, of which the following is a specification, reference being had to the accompanying drawing, forming part thereof.

In said drawing:

Figure 1 is a view in front elevation of an electric lamp embodying my new design, half of the figure being shown in full lines and the other half a marginal outline and dot and dash line to indicate detail of the pattern.

Figure 2 is a side elevation of the same.

I claim:

The ornamental design for an electric lamp, substantially as shown and described.

CHARLES W. LOGAN.
